UNITED STATES PATENT OFFICE.

JAMES R. PRATT, OF DENISON, TEXAS.

ARC-LAMP ATTACHMENT.

1,261,613.

Specification of Letters Patent. Patented Apr. 2, 1918.

Application filed February 17, 1917. Serial No. 149,279.

To all whom it may concern:

Be it known that I, JAMES R. PRATT, a citizen of the United States, residing at Denison, in the county of Grayson and State 5 of Texas, have invented new and useful Improvements in Arc-Lamp Attachments, of which the following is a specification.

This invention relates to improvements in arc lamp attachments, and has particular application to means whereby an incandescent lamp may be substituted for the electrodes 10 of an arc lamp.

In carrying out my invention, it is my purpose to provide an attachment for arc 15 lamps whereby upon the removal of the carbon holder and the electrode holder from the arc lamp an incandescent lamp may be supported in the casing of the arc lamp in proper position with respect to the reflector, 20 and connected with the source of current, thereby enabling the lamp to be operated in the event of defect in the carbon or electrode.

It is also my purpose to provide an attachment of the class described, which will embody 25 the desired features of simplicity, efficiency and durability, and which may be connected and securely fastened within the casing of the arc lamp in the clamp of the electrode holder.

With the above and other objects in view, 30 the invention consists in the construction, combination and arrangement of parts hereinafter set forth and falling within scope of the claim.

In the accompanying drawing:—

Figure 1 is a view in side elevation of an attachment constructed in accordance with the present invention, an incandescent lamp being shown connected thereto.

Fig. 2 is a cross sectional view on the line 40 2—2 of Fig. 1.

Fig. 3 is a view in elevation showing the attachment in position in a conventional form of clamp.

Referring now to the drawing in detail, 45 1 designates a support, which, in the present instance, embodies a vertical shank 2 having the lower end formed with a block 3

opposite from the shank 2 and shaped to fit into the clamp of the electrode holder on the 50 lower end of the arc lamp as shown in Fig. 3. The upper end of the shank 2 is formed with a collar 4 that is offset from the shank, and disposed above the block 3 and formed on the upper edge of the collar 4 is an integral 55 upwardly projecting nipple 5 exteriorly screw threaded to receive one end of an incandescent lamp socket 6, and threaded or otherwise secured in the other end of the socket 6 is an incandescent lamp 7. The 60 current carrying wires are led through the collar 4 and the nipple 5 and connected with the respective binding posts of the socket 6 so that the current may be conveyed to the filament of the lamp 7 and the latter may 65 be energized.

In practice, it is only necessary to remove the carbon holder and the electrode holder and insert the block or base 3 of the support 1 in the clamp of the electrode holder. In 70 this position of the attachment, the lamp 7 is held in proper position relatively to the reflector so that the lamp will be properly focused.

While I have herein shown and described 75 the preferred form of my invention by way of illustration, I wish it to be understood that I do not limit or confine myself to the precise details of construction herein described and delineated, as modification and 80 variation may be made within the scope of the claim and without departing from the spirit of the invention.

I claim:—

An attachment for arc lamps comprising 85 a vertical shank, a block at one end of the shank adapted to engage in the clamp of the electrode holder, a collar on the upper end of said shank offset therefrom, an exteriorly threaded nipple on said collar and projecting 90 upwardly therefrom, and an incandescent lamp socket on said nipple adapted to hold an incandescent lamp within the influence of the reflector on the arc lamp.

In testimony whereof I affix my signature. 95
JAMES R. PRATT.
